CLAIM

The ornamental design for a lunch pail, as shown and described.

DESCRIPTION

FIG. 1 is a perspective view of a lunch pail showing our new design, the undisclosed bottom view being planar and unornamented;

FIG. 2 is a right side elevational view thereof, in a closed position, the opposite side being a mirror image;

FIG. 3 is a rear elevational view thereof; in a closed position;

FIG. 4 is a top plan view thereof, in a closed position; and,

FIG. 5 is a front elevational view thereof in a closed position.

FIG. 1

FIG. 2

FIG. 3

FIG. 4

FIG. 5
